UNITED STATES PATENT OFFICE

JOHN SCHUMACHER, OF LOS ANGELES, CALIFORNIA

METHOD AND MEANS OF APPLYING EDGE-COVERING STRIPS TO PLASTER BOARD

Application filed February 23, 1926. Serial No. 89,998.

This invention relates to a method and means for applying edge covering strips to plaster board.

In the manufacture of plaster board, it is a common practice to supply moist, unset plastic or cementitious material between two advancing sheets of fibrous material with the result that there is produced a board, the top and bottom of which is covered by fibrous covering sheets but the side edges of the board are left open, exposing the plastic or cementitious material. Various means and processes have been devised for causing the fibrous covering material which covers the top and bottom of the board, to extend over and enclose the edges of the boards. These processes are so complex that they have not found any substantial commercial use.

It is the object of the present invention to provide a method and means by which strips of fibrous material of substantially the width of the edges of the plaster board may be passed to the plaster board at the time it is formed in order to adhere to and cover the edges of the finished plaster board.

Another object of the present invention is to provide a means by which the edges of the plaster board may be simultaneously knurled or otherwise roughened and covered with a strip of fibrous material. A further object of the present invention is to provide a method and apparatus by which this finishing and covering of the edges of the plaster board may be carried out continuously as the plaster board is formed.

Various further objects and advantages of the present invention will appear from a description of a preferred form of a method and apparatus embodying the invention, and for this purpose, reference is made to the accompanying drawings in which a preferred form of apparatus is illustrated and by which the preferred method of covering the plaster board edges may be practiced.

In the drawings:

Figure 1 is an elevation partially in vertical section of the apparatus,

Figure 2 is a plan view of the apparatus, certain parts being removed,

Figure 3 is an enlarged elevation of edge strip applying means,

Figure 4 is a side view of the finished board,

Figure 5 is an elevation in section of a modified form of edge strip applying means showing a board produced thereby,

Figure 6 is an elevation at right angles to Figure 5.

Figure 7 is a side view of a board with the edge covering strip, and,

Figure 8 is a side elevation of the roller for forming the same.

Referring to the drawings, the apparatus there illustrated comprises a hopper 2 for holding and supplying plastic or cementitious material which is to be incorporated in the plaster board. 3 indicates a mixer for mixing the plastic or cementitious material with water supplied from a pipe 4. The mixer preferably comprises a trough in which are rotatably mounted mixing blades 5, the blades being mounted upon a shaft 6 driven by a pulley 7. 8 and 9 respectively indicate supply rolls of fibrous covering material which furnish the top and bottom covering sheet for the plaster board to be produced. 10 indicates a sheet or strip of fibrous material supplied from the roll 8 for forming the lower covering sheet of the produced plaster board whereas 11 indicates a sheet or strip supplied from the roll 9 as the upper sheet of the plaster board to be formed. The sheets 10 and 11 are indicated as passing from the rolls 8 and 9 to a plaster board forming and spreading means generally indicated at 12. Suitable advancing means 13 are provided for continuously conveying the plaster board being formed to the discharge end of the apparatus, such advancing means being indicated as comprising a conveyor 16.

The spreading and forming means 12 of the apparatus include an upper roller 20 and a lower roller 21 spaced apart to determine the thickness of the finished board. As the sheets 10 and 11 are fed between the rollers 20 and 21, plastic or cementitious material is fed from the hopper onto a box 17 likewise positioned on the advancing

means 13 from which the plastic or cementitious material is spread by the rollers 20 and 21 between the sheets 10 and 11 and formed into a proper thickness of plaster board. In so far as the apparatus and method of forming plaster board has been particularly described, it is similar to the generally accepted apparatus and method particularly described and claimed in Patent 18 No. 1,176,322, granted to John Schumacher and Joseph E. Schumacher, March 21, 1916.

In accordance with the present invention, means are provided to feed the fibrous covering material strips 10 and 11 to the spreading and forming means so that the strips will be substantially equal in length to the width of the rolls 20 and 21 of the spreading and forming means. This, of course, may be accomplished by the use of rolls 8 and 9 20 of fibrous covering material substantially corresponding in width with that of the rolls 20 and 21. In order to insure the sheets as supplied to the spreading and forming means 12 will be of the proper thickness to 25 correspond with the width of such means, it is generally preferable to provide a trimming means for the sheets positioned in advance of the rolls 20 and 21. 22 and 23, respectively, generally indicate trimming means for the respective sheets 10 and 11. This trimming means may be of any desired or preferred form, such as disk knives 24 and 25 respectively, and may be driven in any desired manner.

35 Where mention is made of the provision of the feeding or trimming of sheets 10 and 11 to correspond with the width of the rolls 20 and 21 of the spreading and forming means, it is understood that the sheets 10 and 11 are made to be equal to the length of the rolls 20 and 21 as they pass therebetween. Inasmuch as the contact between the fibrous covering material and the moist plastic or cementitious material supplied from 40 box 17 causes in operation a slight swelling of sheets 10 and 11 amounting to a fraction of an inch, the trimming of the sheets by the device 22 and 23 should be governed accordingly. This makes the sheets 10 and 11 45 as cut by the trimming means, slightly narrower than the width of the rolls 20 and 21.

In accordance with the present invention, a method and means is provided for continually smoothing the edges of the plaster board as the board is formed in order that a smooth clean edge will be obtained. For this purpose, the invention preferably includes the trowels described and claimed in my copending application Serial No. 11,169, 55 filed February 24, 1925, Patent No. 1,581,328, issued April 20, 1926. Such trowels are generally formed by providing disk flanges 26 on the ends of one of the rolls 20 and 21 flush against the other roller so that the 60 movement of such flanges down and across

the plaster board as it is formed will smooth the edges and turn in the corners of the fibrous covering material.

The plaster board 27 indicated as continuously passing as formed from the forming and spreading means 12 is passed while still in an incompletely set condition between a pair of opposed knurled rollers 28 and 29 which are mounted to revolve in the same plane as the plane of the traveling plaster board and having their facing edges engaging the edges of the plaster board. The edges of the rollers 28 and 29 are slightly knurled in order to produce a slight roughening or knurling of the edges of the produced plaster board, and coating with each of the rollers 28 and 29 are rolls 30 and 31. The rolls 28 and 29 also preferably are provided with disk flanges 32 and 33 for extending over the top of the plaster board passing 85 the rolls.

35 and 36 respectively indicate rolls of narrow fibrous covering material which is supplied continuously from the rolls to the rolls 28, 30 and 29, 31, respectively, and thereby conveyed into position against the side edges of the produced plaster board 27. By this process and means, said strips are caused to adhere to the incompletely set plastic material of the board and properly cover 90 the normally exposed edges of such plaster board. If desired, these strips may include material for hardening the edges of the plaster board or material for assisting the strips in adhering to the plaster board or be impregnated or caused to carry other ingredients for like or similar purposes.

Referring to Figures 5 and 6, it sometimes is desirable to form a longitudinal groove in the side of the plaster board and the method and apparatus of the present invention provides a means by which this longitudinal groove may be formed and covered with fibrous material simultaneously. For this purpose, the edge of the forming roller 29^a 110 is caused to have an outwardly extending tongue 40 of a size corresponding to the depth of the desired groove to be produced in the plaster board. The use of a roll of this type together with the use of strips of paper of a size sufficient to cover the tongue 40 and extend the width of the roller 29^a 115 will permit the simultaneous forming and covering of the desired longitudinal groove in the plaster board.

While the particular form of the invention herein described is well adapted for accomplishing the objects of the invention, it is understood that various modifications may be made without departing from the principles of the invention and the invention includes all such modifications and changes as come within the scope of the appended claims.

I claim:

1. In a process of producing plaster board, the steps of smoothing the edges of plaster board as the same is formed by the incorporation of plastic or cementitious material between fibrous covering sheets and then 5 knurling said edges and supplying thereto thin sheets of fibrous covering material to cover the edges of said produced board.
2. A method of forming plaster board 10 which includes continuously passing strips of fibrous covering material between spreading and forming rolls, continuously supplying plastic or cementitious material between the sheets at the rolls, continuously smoothing 15 the edges of the board as formed to form a plaster board with smooth edges, continuously knurling and supplying to the edges of the board strips of fibrous covering material to cover the plastic or cementitious material at the edges of the plaster board.
3. An apparatus for forming plaster board comprising plaster board forming means, means for smoothing the edges of the board as formed, means for advancing 20 the plaster board in said forming means, knurled edged rollers disposed at opposite sides of said latter means for engaging the formed plaster board, and means for supplying edge covering strips to said rollers.

30 Signed at Los Angeles, California, this 13 day of February 1926.

JOHN SCHUMACHER.
